DESIGN FOR A REPAIR LOCK FOR METAL CASTINGS OR THE LIKE

Lawrence B. Scott, Columbus, Ohio

Application August 18, 1941, Serial No. 102,915

Term of patent 14 years

To all whom it may concern:

Be it known that I, Lawrence B. Scott, a citizen of the United States of America, residing at Columbus, in the county of Franklin and State of Ohio, have invented a new, original, and ornamental Design for a Repair Lock for Metal Castings or the like, of which the following is a specification, reference being had to the accompanying drawing, forming a part thereof.

Figure 1 is a perspective view of a repair lock for metal castings or the like, showing my new design;

Figure 2 is an end elevational view; and
Figure 3 is a side elevational view.

I claim:

The ornamental design for a repair lock for metal castings or the like, as shown.

LAWRENCE B. SCOTT.
